United States Patent Office.

EDWIN J. TOO, OF MADISON, IOWA.

Letters Patent No. 80,843, dated August 11, 1868.

IMPROVEMENT IN LAMP-BURNERS.

The Schedule referred to in these Letters Patent and making part of the same.

TO ALL WHOM IT MAY CONCERN:

Be it known that I, EDWIN J. TOO, of Madison, in Lee county, and State of Iowa, have invented certain new and useful Improvements in "Lamp-Burner Attachments;" and I do hereby declare that the following is a full, clear, and exact description thereof, reference being had to the accompanying drawings, through letters of reference marked thereon, forming part of this specification, and in which—

Figure 1 represents a side elevation of a burner embracing my improvement.

Figure 2, a transverse section of the same.

Figure 3, a top view thereof.

Figure 4, an inverted view.

Figures 5, 6, and 7, detached views of one of the supports of cone and chimney.

This invention relates to that class of burners in which the cone or deflector is elevated above the air-screen, and sustained in position by suitable supports, and wherein the chimney passes down over the said cone and its supports, such as are known in the market as "sun," "comet," "solar," or "diamond" burners, the main objection to which is the inconvenience in trimming and lighting, owing to the cone being rigidly attached to the air-screen or other part of the burner, and the necessity for removing the chimney for such purpose. Some attempts have been made to remedy this evil, by hinging the central part of the deflector to an annular plate, which is rigidly attached to the air-screen, or by making the cone and air-screen detachable from the burner; but in all these, whilst they are only a partial remedy, they involve additional expense in manufacture.

The object of my invention is to simplify the construction, render the wick-tube perfectly accessible, without detaching even the chimney-glass; and it consists in a novel manner of supporting and connecting the cone with the air-screen or other suitable part of the burner; in connecting the cone with and at a proper elevation within the chimney-glass, so that they may be removable together or separately; in the construction of the hinge-joint, by which the chimney-holder and cone are connected with the burner; in the arrangement of the spring-retaining catch, formed in one piece, with one of the cone and chimney-supports; in the peculiar construction of the supporting-pieces, so as to give both rigidity and elasticity where required; in so constructing and applying the chimney-supports that they will adapt themselves to the variations in size of the chimneys; and, whilst they act as chimney-supports, they also attach the cone thereto, and retain it in suitable position therein; and in constructing the supports and clamps, forming the chimney and cone-holders, and also the retaining-catch of one of them, each in one continuous piece of metal, so as to require riveting only in one place; also in the insertion of a valve in the vapor-tube for the more perfect prevention of explosion.

To enable others to make and use my invention, I will proceed to describe its construction and operation by referring to the drawings, in which—

A represents the air-screen or distributor, which may be a flat, concave, or convex disk, or of any other suitable or ornamental formation, to which are attached the wick-tube B, screw-boss C, for forming the connection with the body of the lamp, the vapor-tube D, and the ratchet or spur-wheel, shaft and mill-head, common to some such lamps, for raising the wick in the tube, and within the central boss of the air-screen is a diaphragm, G, fitting closely around the wick-tube and vapor-tube to cut off any communication between the lighted wick, through the aperture into which the spring *a* locks, and that portion of the wick-tube penetrated by the spur-wheels, which otherwise might cause explosion.

E represents the cone or deflector, the use and position of which are well understood. To this cone, I attach four, more or less, spring-plates F, which are first formed out of sheet metal, rolled or otherwise tempered to give it elasticity, and of variable width or thickness, to give more or less elasticity at different parts of their length, as represented in fig. 7. These spring-plates are then bent into the form represented in fig. 5, and attached, by riveting or otherwise, to the cone E, and one of said spring-plates is extended in length from its wider end, and somewhat tapering therefrom, so as to form in connection therewith the catch-spring *a*, for the purpose of locking the cone in proper position over the burner, by catching into an opening in the elevated central portion of the air-screen A, or other convenient attachment to the burner.

The air-screen A has also formed in it, near its periphery, one or more indentations *b*, or, it may be, apertures to form the seat or seats of the lower bent ends of the spring-supports F, these indentations conforming in size and shape to the width and curvature of the lower portion of said spring-supports, and in which one of them is connected by passing a wire therethrough and through the loop of the support, or by indenting the end portions of such indentations, or partially severing such portions, so as to lock into the loop of the support, thus forming a simple and effective hinge-joint. It is only necessary that the one support, with which this hinge-connection is made, should be seated in an indentation in the air-screen; the others may rest upon the flat surface thereof, but, in that case, they must be made correspondingly shorter than the hinged one, in order that the cone may set at right angles to the wick-tube.

These spring-supports F not only sustain the cone, but form a clamp-holder for the chimney-glass, a portion of which is represented in red lines in fig. 2, from which it will be seen that, as they are only rigidly attached to the cone and free at the lower end, they will readily conform to slight variations in the diameter of such chimneys. This same effect might be attained even if the lower ends of the supports were also rigidly connected to a ring, and that hinged to the air-screen, but that construction, in case of a smaller-sized glass being used, would elevate the cone slightly further from the wick-tube than would be the case with one of larger diameter; for this reason the free support is preferable, as well as being less expensive to manufacture.

The hinged connection of the support being formed within the periphery, or the outer extremity of the air-screen A, or any attachment thereto, when the chimney is turned aside, to trim or light the lamp, the outer or clamping-spring portion strikes and rests upon such outer portion of said screen, which causes the chimney to be gripped with greater firmness, when in a position most liable to become detached, and is thus held so securely that any ordinary shaking would not separate it from the holder.

In order to guard against explosions, which arise most frequently from the sudden change of temperature to which the body of the lamp is subjected, as in passing from a warm into a cold atmosphere, whereby a partial vacuum is caused in such vessel, the effect of which is to draw the flame of the burner down the vapor-tube by its side, and thus ignite its contents, I insert a check-valve, *e*, with vapor-tube D, opening upwardly, so that any pressure of the expanding vapor within said vessel may have free escape; but the moment that pressure ceases, or a partial vacuum is caused, the valve will close and cut off all communication between the flame and the contents of the body of the lamp, and thus prevent the possibility of explosion from such cause.

Having thus described my invention, what I claim as new, and desire to secure by Letters Patent, is—

1. The springs F, which are so constructed as not only to act as a support to the elevated cone E, but, at the same time, to serve to clamp the chimney, whether the same be hinged to or have spring-snap connection with the foraminous air-screen A, substantially as herein shown and described.
2. The hinge-joint, formed by the bend of the spring-support F, in connection with an aperture or depression in the disk A, or any attachment thereto, substantially as shown and described.
3. The spring-catch *a*, formed by the extension of the spring-support F, and arranged in relation to the cone E, and locking into the central elevated portion of the air-screen, or other convenient attachment to the burner, substantially as shown and described.
4. The spring-clamps F, constructed with variable widths or thicknesses, for the distribution of the spring and holding-parts, substantially as set forth.
5. The clamps F, constructed of one continuous strip of metal, and serving to support the cone within the chimney, and to support and connect both with the foraminous screen, substantially as described.
6. The application of the valve *e* to the vapor-tube of a lamp-burner, substantially as and for the purpose set forth.

EDWIN J. TOOF.
